UNITED STATES PATENT OFFICE.

THOMAS W. PORTER, OF CHELSEA, MASSACHUSETTS.

VEHICLE-POLE.

SPECIFICATION forming part of Letters Patent No. 397,934, dated February 19, 1889.

Application filed October 6, 1888. Serial No. 287,364. (No model.)

To all whom it may concern:

Be it known that I, THOMAS W. PORTER, of Chelsea, in the county of Suffolk and State of Massachusetts, have invented a new and useful Improvement in Vehicle-Poles, which will, in connection with the accompanying drawings, be hereinafter fully described, and specifically defined in the appended claims.

In said drawings, Figure 1 is a top plan view of a vehicle-pole embodying my improvements, the front portion being broken away to allow a larger scale of drawing. Fig. 2 is a detached side elevation showing a part of the cross-bar, the coupling thereto secured, and a portion of the oblique side stay and shank of the draft-eye. Fig. 3 is a detached sectional top plan view, the section being taken as on line Z Z, Fig. 2, and the plan showing the draft-eye, the shackle, and a portion of the axle. Fig. 4 is a vertical longitudinal section taken as on line X, Figs. 5 and 6, and showing the coupling, the rear portion of the cross-bar, and the eyebolt that locks the draft-eye in the coupling. Fig. 5 is an under side plan view of the coupling alone. Fig. 6 is a vertical section taken on line W, Fig. 2, and viewed as from the left in that figure. Fig. 7 is a detached plan view of the coupling with the shank of the draft-eye in place therein and with a change in the locking device. Fig. 8 is a transverse section taken on line V, Fig. 7. Fig. 9 is also a section taken on line V, Fig. 7, but showing another change in the locking device. Fig. 10 is a vertical section taken in the axial line of the cross-bar at its lineal center, and showing the pole and cross-bar coupling in transverse section in its relation to the cross-bar. Fig. 11 is a transverse vertical section taken on line S, Fig. 1. Fig. 12 is a similar section taken on line R, Fig. 1. Fig. 13 is a side elevation of the rear portion of the pole, and showing the cross-bar in cross-section and as secured to the pole by the coupling. Fig. 14 is a vertical section taken in the axis of the pole and coupling and transverse to the cross-bar.

This invention relates to that class of poles which are employed in light vehicles, (carriages and sleighs,) to which vehicles either one or two horses may be harnessed, thus requiring the shifting from shafts to a pole,

and vice versa, and as in many instances—such as in livery-stables—it is necessary to use the same pole in divers vehicles in which, owing to want of any established standard, the shackles are at diverse distances apart, it is therefore requisite that the draft-eyes of the pole be adjustable in such behalf; and my invention relates to means for adjusting, locking, and supporting said draft-eyes, in means for connecting the stays with the cross-bar, and in means by which the pole and cross-bar are coupled together, as will, in connection with said drawings, be hereinafter fully described, and pointed out in the claims.

Referring again to the drawings, A represents the pole, B the evener, C C the whiffle-trees mounted on the evener, and D the cross-bar, all which are in and of themselves old, common, and well known. Said cross-bar is shown tubular, and preferably formed of gas-pipe, and for the purpose of securing it to the pole I have provided the metallic coupling E, formed in two parts or subdivided by horizontal line a, said parts being formed with an eye, b, to receive bar D; also with straps c, extended along the top and bottom of the pole, with short side cheeks, d, which, in conjunction with straps c, produce the short socket e, in which to insert the rear part of the pole, said coupling having corresponding holes in its upper and lower parts to receive the securing-bolts d g, the former of which is close to bar D and serves to clamp it firmly in the coupling. A pin, i, is formed in one or both halves of the coupling to enter a corresponding hole in the bar to insure it from either rotative or lineal displacement, and a chamber or recess, h, formed in the interior of eye b, renders it feasible to "ream" the hole in said eye to a standard size for the reception of bar D.

To each end of bar D, I secure a metallic coupling, F, having in a portion of its length an axial passage to receive freely shank H of draft-eye I, which, as shown, is by pivot-bolt j secured in shackle J, which by clip K is secured on axle L in the well-known manner. When bar D is of metal, as shown, it and the inner end of couplings F are correspondingly threaded and secured together, as shown; but if bar D were of wood, then the

inner portion of said couplings would preferably terminate in straps, as does coupling E at the intersection of said bar with pole A.

To secure shank H rigidly in position in coupling F when properly adjusted, I preferably employ eyebolt k, which is inserted in the rectangular open slot l of the coupling, (which latter is at that point slightly enlarged on its under side for that purpose,) 10 while the bolt-like portion extends up through the circular passage m and has threaded upon it nut n, which is seated upon boss p, formed upon the top of the coupling.

It will be obvious that as shank H passes 15 freely through the eye of bolt k, therefore when nuts n are slackened the draft-eyes I may be adjusted at the requisite distance apart to enter shackles J, when, by tightening nuts n, the draft-eyes are rigidly locked in couplings F.

Instead of forming coupling F with slot l and employing the eyebolt k, the rear end of the coupling may be formed with several longitudinal slots, w, through its shell, and a binding-nut, t, be duly threaded to the taper portion of the coupling, so that by actuating said nut the shank H may be firmly gripped or be liberated at will, the nut being preferably formed with a rectangular portion, u, to receive an actuating-wrench; or, if preferred, the shank H may be locked by means of a set-screw, v, threaded in the coupling at boss p, as shown in Fig. 9.

The oblique stays G are at their front ends 35 secured to the pole in the usual manner; but at their rear ends they are secured by screws to the offsets q s, formed upon couplings F, thus giving stability to all the parts and securing said couplings from possibility of rotation and consequent slackening of their threaded contact with cross-bar D.

I form the rear end of stays G at right angles to the axis of the pole, to which to attach the rear end of the cheek-straps of the 45 evener, the front ends of said straps being secured to loops y on the evener, a knob, x, being formed upon the end of said stays to hold the strap in place thereon; or, if preferred, the rear end of said stay may terminate in a 50 loop or eye to which to attach the straps.

I am well aware that it is old to employ in carriage-poles a cross-bar that is tubular either in part or the whole of its length, and that it is also old to insert the shank of the 55 draft-eye in the axial passage in such hollow bar, and that it is common to secure said shanks in the bar by a set-screw threaded in the wall of the bar, or by correspondingly threading the shanks and interior of the bar, 60 so that the shanks may be turned inward or outward.

I am also aware that it is common to secure the rear ends of stays G to the ends of bar D by either bolting them thereto or by forming 65 a ring on the stay to receive the end of the bar.

I am also well aware that it has long been

common to unite two parts of a carriage where one is transverse to the other—such as the pole and cross-bar—by a metallic coupling, and the several locking devices are in and of themselves old; hence I do not broadly claim any of said devices, my invention consisting, broadly, in the combination of a hollow metallic coupling, the cross-bar, and draft-eye, and the combination of such coupling with the cross-bar and pole-stays; also, the combination of such coupling and a clamping device for securing the draft-eye therein, and also in the novel features of the coupling that 75 unites the pole and cross-bar, all as expressed in the appended claims.

I claim as my invention—

1. In a vehicle-pole, a metallic coupling 85 formed to receive the end of the cross-bar, and with an axial passage therethrough to receive the shank of the draft-eye, and having a locking device to rigidly secure said shank in position as adjusted, substantially as specified.

2. The metallic coupling F, formed to receive a cross-bar, and with a diminished axial 90 passage to receive shank H, and having a transverse passage consisting of slot l and hole m to receive an eyebolt, substantially as specified.

3. The combination of bar D, coupling F, having an axial passage, draft-eye I, having shank H, adjustable in the coupling, and a locking device whereby the draft-eye is rigidly secured in said coupling when adjusted, 100 substantially as specified.

4. The combination of cross-bar D, coupling F, draft-eye shank H, and eyebolt k, provided with nut n, all substantially as specified.

5. In a vehicle-pole, the combination, with cross-bar D and stays G, of a tubular coupling the axis of which is an extension of that of said bar, and having an offset or offsets to receive said stays, substantially as specified.

6. The combination, with bar D and stays G, of coupling F, having the hollow threaded offsets to receive the stays and securing-bolts, substantially as specified.

7. The combination, with pole A and cross-bar D, of coupling E, formed in two parts, with an eye, b, to receive said bar, a recess or chamber, e, to receive the rear end of the pole, the perforated securing-straps c to receive bolts g, and a transverse passage near eye b 110 to receive the bar-clamping bolt d, substantially as specified.

8. The divided coupling E, formed to receive the pole, and with a circular transverse passage to receive bar D, as described, and pin i, formed integrally with one of the halves of said coupling and adapted to interlock with and secure said bar D from rotary or lineal displacement, substantially as specified.
